[57] ABSTRACT

For storing packages or the like in an attic crawl space, having a trap door access opening circular platforms of diameter considerably larger than the maximum dimension of the access opening are rotatably mounted on horizontal floor sections covering the crawl space floor joists at locations which can be reached by a person standing at or in the trap door opening. Castors around the outer edge of each circular platform support it for easy rotation in either direction on these floors; and a pivot pin through the center of the platform and the floor on which the platform is supported serves to keep each platform positioned immediately adjacent the crawl space opening so that coded boxes or bundles can be stored thereon and easily reached, lazy Susan style. A chart, stored adjacent to the platforms and floors, is provided for indicating the nature and contents of each bundle. These circular platforms are each made up of two hinged pieces which, when in their folded over, collapsed condition, will fit through the maximum dimension of this crawl space opening.

SYSTEM AND APPARATUS FOR STORING PACKAGES

BACKGROUND OF THE INVENTION

In a typical American home of today, at least a portion of the space between the slanted outer roof and the uppermost room ceiling is unfinished. The average American family living in such a house accumulates a variety of clothing and equipment which is used seasonally (such as gear for participating in summer camping and winter sports, and clothing designed for use during a particular season), or on specific periodically recurring occasions (Thanksgiving, New Years, Christmas, Easter, Halloween, etc.). This average family has a great need to store the equipment related to such seasons or occasions in such a manner that it will not be taking up room in the living area of the house and in such a manner that it is readily available and can very easily be located when it is needed.

The typical attic crawl space is unfinished with bare roof rafters supporting the roof sheathing and with open ceiling joists having Sheetrock ceiling sheets nailed on the bottom thereof. Typically, bulk vermiculite or rock wool is poured between the floor joists. Ventilators to the outside are provided to insure that the temperature and the moisture content of the air in the crawl space is maintained commensurate with the outside ambient temperature and humidity conditions to prevent undue condensation and moisture permeation problems.

Changes in temperature causing contracting and expansion of the air into and out of crawl space through these ventilators, the wind conditions outside of the house, and the movement of people in the crawl space in the act of storing or retrieving articles all causes the insulating materials and also the ambient dust and airborne pollutants to be deposited throughout the crawl space and, specifically, over any articles stored therein. This makes it advisable to store all gear inside of cartons. This makes it impossible to identify the contents of the cartons from the outside; and makes it necessary to crawl into the space to identify the contents of the cartons either by opening the carton or by reading the outside of the carton if the contents have been listed there.

SUMMARY OF THE INVENTION

As shown, an apparatus of the present invention includes two plywood pieces cut into shapes so that when they are hinged to each other, they form a complete circular platform. Castors around outer edge portions of this platform support it on a floor section consisting of a series of boards which have been nailed to the ceiling joists and which form a rectangular base of dimension sufficiently to support the castors of the circular platform.

A pivot pin extending through the platform and the floor insures that the platform will rotate with respect to the floor, but will not move off of it.

A plurality of numbered, lettered and/or color coded empty containers are provided sufficient to substantially cover a particular platform at least one layer deep. Typically, each platform can be painted in a distinctive color and containers of the same color can be serially numbered or lettered on all faces for use only on that platform. A chart identifying each plat-

form and providing a space for each of the consecutively numbered containers is provided so that the contents of each container can be noted in the space provided. This chart can be of a dimension so that it will fit between one of the platforms and its floor section and between its pivot pin and ring of castors so it can be reached by a person standing at the trap opening by extending his hand past the castors and between the platform on the floor space.

When the materials and equipment relative to a certain occasion or season or event in the life of the family are to be stored, they will be put in one or more of the containers associated with a particular platform and notations about the contents of these containers will be made on the appropriate chart space provided. The containers are closed to protect against dust, and then these resulting packages are introduced through the trap opening and deposited on the particular platform.

A plurality of retaining fingers, extending upwardly from the outer periphery of the platform, form a retaining ring which keeps the packages from sliding off of the platform.

The platform will then be rotated to carry the package to a position away from the crawl space access opening so that subsequent packages can be positioned on the platform adjacent the opening.

When it is desired to use the equipment in a particular package, the platform is rotated until the container number is visible and until the package is immediately adjacent the crawl space, at which point it is removed through the trap door opening, the equipment taken from the container, and the container then replaced empty until such time as the equipment has served its purpose and can once again be stored.

IN THE DRAWINGS

FIG. 1 is a perspective view of a fragmentary portion of an attic crawl space and trap door access opening showing one of the invention located adjacent to said opening;

FIG. 2 is an enlarged vertical sectional view taken on the line 2—2 in FIG. 1;

FIG. 3 is an enlarged vertical view taken on the line 3—3 in FIG. 2;

FIG. 4 is a bottom plan view of the platform in FIGS. 1, 2 and 3; and

FIG. 5 is a view of a chart designed to be stored between the floor and one of the platforms and illustrating the coding for the containers and the platforms.

DESCRIPTION OF THE PREFERRED EMBODIMENT

Apparatus for storing packages includes a plurality of circular platforms 10, only one of which is illustrated in the drawings. As shown, the platform consists of a first platform section 11, and a second platform section 12 hingedly mounted thereto at a top surface thereof as at 13. A plurality of castors 14 are mounted around the periphery of the circular platform to support it on a floor section 15 which is built up of a plurality of floor boards 16 nailed to ceiling joists 19 of an attic crawl space having a trap door opening 20 therethrough. This trap door access opening is bounded by a frame 21. The access opening 20 opens from the attic crawl space through the ceiling into the occupied part of the house.

As disclosed, the space between the ceiling joists 19 is filled with bulk insulating material 22 such as vermiculite, rock wool or glass wool.

In order to insure that the platform 10 doesn't move laterally with respect to the floor section 15, a pivot pin 25 extends down through an opening 26 provided in the first platform section 11 and through an opening 27 in one of the floor boards 16 of the floor section 15. As shown, a bushing 28 is fitted in this opening 27, and a spacer collar 29 is situated between this bushing and the platform section 11 to assist in maintaining the platform at the height established by the castors 14.

Because the floor boards 16 are relatively narrow, they are easily inserted through the trap door opening 20 and are nailed to the floor joists 19 to provide a smooth flat supporting surface for castors 14 of the circular platform 10.

In order to get the most storage space practicable, the diameter of the circular platform 10 is larger than the greatest diagonal dimension across the ceiling opening 20 and through the frame 21. The purpose of the hinged first and second sections of this circular platform 10 is to allow minimum overall dimension of the circular platform to be temporarily reduced so that the platform can be introduced through the frame 21 and the opening 20. Once inside of the attic crawl space, the circular frame is opened out of the position as seen in FIGS. 1, 2 and 4, and positioned so that the opening 26 is in vertical alignment with the opening 27. The bushing 28 is inserted through the opening 27 in a floor board 16, the pivot pin 25 is inserted through the opening 26, the spacer collar 29 is slid over this pin, and the end of the pin is slid through the central cylindrical opening in the bushing 28.

A plurality of retaining fingers 30 extends upwardly from the outer cylindrical edge of the platform 10 in position to prevent packages stored on the platform from being accidentally pushed therefrom.

While only one such apparatus of the present invention is shown, it is to be understood that a similar or exactly identical arrangement of apparatus could be established exactly opposite the opening 20 and frame 21, thus doubling the amount of storage space available for use in a manner to be described. Further, by building up additional floor sections to the left and right of the frame 21 as seen in FIG. 1, two additional circular platforms can be installed.

The system for utilizing the apparatus of the invention involves establishing a code identity for each platform. For example, the platform shown in FIG. 1 can be assigned the code letter A, and/or can be painted with an identifying color such as red, for example. Other platforms can be identified by other letters and/or can be painted colors such as yellow, blue or green.

A series of containers 31 will be provided which are also identified with the same code as used to identify the platform. Depending on the nature of the equipment to be stored, these containers can be constructed out of any suitable material. For example, cardboard boxes could be utilized which would be painted a distinctive color, for example, red, or an identifying symbol such as letter A can be marked on each such

container to be utilized with a particular platform. Each of the containers associated with a particular platform will be serially numbered on all six faces thereof so that it can be easily identified as long as at least one face thereof is visible.

A chart 32 is provided in which spaces are provided for each serially numbered box for each coded platform.

When it is desired to store seasonal clothing, for example winter jackets, a container 31 of suitable size will be chosen, for example, the red coded container serially numbered 1, and the winter jackets will be placed inside, the resulting package closed, and a person standing near or in the trap door access opening 20 to the crawl space will position the red coded container "1" on the red platform 10. The notation "winter jackets" will be written in the square provided on the chart 32. Other equipment can be placed in other containers, the chart labeled appropriately, and these packages put on the platform 10 as the platform is rotated round to make room for them. The master chart showing the location of the equipment in each of the boxes can then be slid between the platform 10 and the floor section 15 to have position substantially as shown in dotted lines in FIG. 4, between the outer ring of castors 14 and the center opening 26 and pin 25. As other equipment is to be stored, the chart 32 will be removed and additional notations will be made in the appropriate squares as to the contents of each of the packages on the platforms.

The embodiments of the invention in which an exclusive property or privilege is claimed are defined as follows:

1. Apparatus for storing equipment in an unfinished attic crawl space having a rectangular trap door access opening and ceiling joists defining a portion of the bottom of such space, such apparatus including a relatively smooth horizontal floor section supported on said ceiling joists, a circular platform of diameter substantially greater than the maximum dimension of said access opening and situated on said floor section in adjacent tangential relationship to a portion of the periphery of said opening; a plurality of castors mounted on the underside of said platform to support said platform on said floor section; guide means cooperating with said platform and said floor section for permitting rotation of said platform on said castors with respect to said floor section while preventing lateral movement of said platform with respect to said floor section; said platform being made up of two plane sections meeting on a straight line; and hinge means joining said sections for movement between an open, operating position and a folded position, one over the other; said platform being of size and shape to fit through said opening when in folded position.

2. The combination as specified in claim 1 and upstanding retaining means around the outer periphery of said circular platform section.

3. The combination as specified in claim 1 and a plurality of containers of size and shape to fit through said opening, said containers and said platform being identified by a common visual code, and said containers being serially numbered.
